US00D439324S

(12) **United States Design Patent** (10) Patent No.: **US D439,324 S**
(45) Date of Patent: **** Mar. 20, 2001**

(54) **TURBINE BLADE**

(75) Inventor: **David Wood**, Maitland (AU)

(73) Assignee: **Energy Australia**, Sydney (AU)

(**) Term: **14 Years**

(21) Appl. No.: **29/102,283**

(22) Filed: **Mar. 22, 1999**

(30) **Foreign Application Priority Data**

Sep. 22, 1998 (AU) 2985/98

(51) LOC (7) Cl. **23-04**

(52) U.S. Cl. **D23/413**

(58) **Field of Search** ..... 416/123 R, DIG. 5,
416/228, 235, 123 A, 243; D23/411, 413,
370, 380

CLAIM

The ornamental design for "turbine blade," as shown.

DESCRIPTION

FIG. 1 is a perspective view of a turbine blade showing my new design;

FIG. 2 is a top plan view thereof;

FIG. 3 is a front elevational view thereof;

FIG. 4 is a bottom plan view thereof;

FIG. 5 is a rear elevational view thereof;

FIG. 6 is a left side elevational view thereof; and,

FIG. 7 is a right side elevational view thereof.

1 Claim, 2 Drawing Sheets

FIG. 4

FIG. 5

FIG. 6

FIG. 7
